UNITED STATES PATENT OFFICE

161,489

PORTABLE OIL CHANGER

Maurice A. Michaels, Montclair, N. J., assignor to
The Oiljak Manufacturing Co., Inc., Montclair,
N. J., a corporation of New Jersey

Application April 19, 1949, Serial No. 2,136

Term of patent 7 years

(Cl. D14—3)

To all whom it may concern:

Be it known that I, Maurice A. Michaels, a citizen of the United States, residing at Montclair, in the county of Essex and State of New Jersey, have invented a new, original, and ornamental Design for a Portable Oil Changer, of which the following is a specification, reference being had to the accompanying drawing, forming part thereof.

Figs. 1 and 2 are front perspective views of a portable oil changer, embodying my new design;

Fig. 3 is a perspective view of the rear side of the same; and

Fig. 4 is a top plan view thereof.

I claim:

The ornamental design for a portable oil changer, substantially as shown.

MAURICE A. MICHAELS.
